Patented June 22, 1926.

UNITED STATES PATENT OFFICE.

JAMES E. TAYLOR, OF SAN ANTONIO, TEXAS.

SEESAW ROCKER.

Application filed June 27, 1924. Serial No. 722,787.

This invention aims to provide a simple rocker, adapted to be used by two or more persons, and so constructed that it will not tip over endwise. Another object of the invention is so to construct a device that parts thereof will be yieldable, thereby giving the structure an irregular motion as it oscillates.

It is within the province of the disclosure to improve generally and to enhance the utility of devices of that type to which the invention appertains.

Although a preferred form of the invention has been shown, it will be understood that a mechanic, working within the scope of what is claimed, may make changes without departing from the spirit of the invention.

In the drawings:—Figure 1 is a side elevation wherein parts are broken away; Figure 2 is a top plan; Figure 3 is a section on the line 3—3 of Figure 1.

The device forming the subject matter of this application comprises curved bows 1, which are resilient. Disposed below the bows 1 and located symmetrically with respect to the bows, so far as the length of the bows is concerned, are curved rockers 2 which are resilient, the bows and the rockers ordinarily being made of wood. The rockers 2 have a more pronounced curvature than do the bows 1. Securing elements 3 connect the ends of the rockers 2 with the bows 1. Struts 4 are secured at their upper ends, as at 5, to the bows 1. The rockers 2 are engaged intermediate their ends by the struts 4, but are not secured to the struts. The bows 1 carry a platform made up of slats 6 attached to the bows by securing devices 7. The securing elements 3 which connect the ends of the rockers 2 with the bows 1 may also pass through the endmost slats 6, as indicated in Figure 1, to aid in holding the said slats and to form a firm anchorage for the securing elements 3. The bows 1 are provided at the upper ends with a back including slats 8.

Vertical seat supports 9 are secured at their lower ends to the bows 1 in alignment with the ends of the rockers 2, and in abutment with the outer edges of the terminal slats 6 of the bottom. The seat supports 9 carry arms 10 which extend backwardly between the back slats 8 into engagement with the bows 1. The arms 10 are not connected to the bows 1. Seats 11 are provided and in-

clude side pieces 12 and cross members 14 connecting the side pieces. The rear ends of the side pieces 12 of the seats rest on the bows 1, but are not connected thereto. Diagonal braces 15 are shown. The braces are attached at 16, intermediate their ends, to the seat supports 9 and to the side pieces 12 of the seats 11. At their upper ends, the braces 15 are secured at 17 to the arms 10. The braces 15 are attached at 18, intermediate the ends, to the bows 1. The lower ends of the braces 15 are crossed as at 19 and are secured at 20 to the struts 4.

One of the advantages of the device is that it will be practically impossible to overturn it endwise. When the device is rocked into the dotted line position of Figure 1, it will be supported not only by the rockers 2 but by the bows 1, and overturning of the structure, endwise, will be avoided. Since the rockers 2 are resilient, and since they are not connected to the struts or posts 4, the rockers can yield as the device is oscillated, and the device will be given a peculiar jumping motion which will appeal to a juvenile occupant. It is to be observed that, from the point 21 where the bows 1 and the rockers 2 are connected, to the upper ends 22 of the bows, the bows are absolutely free and are not joined to the seat 11 or to the arms 10. This gives the backs for the seats resiliency and freedom of motion, as the occupants of the seats press backwardly and produces added irregularity in the movement of the device as it is oscillated.

What is claimed is:—

1. In a device of the class described curved bows, seats located adjacent to the ends of the bows, the bows being extended behind the seats to form backs therefor, and curved rockers located below the bows and mounted on the intermediate portions of the bows, the rockers being of a more pronounced curvature than the bows, whereby the intermediate portions of the rockers and the intermediate portions of the bows will support the device when the same is rocked toward an extreme position.

2. In a device of the class described, curved bows seats located adjacent to the ends of the bows, and curved rockers located below the bows and secured at their ends to the bows, the rockers being shorter than the bows, and being resilient.

3. A device of the class described, constructed as set forth in claim 2, and fur-

ther characterized by the fact that those portions of the bows which lie between the ends of the rockers and the extremities of the bows are resiliently movable, independently of the seats.

4. In a device of the class described, curved bows, and seats supported from the intermediate portions of the bows, the ends of the bows forming the backs of the seats and being resiliently movable relatively to the seats when the occupants of the device press against the backs.

5. A device of the class described, con-

structed as set forth in claim 4, and further characterized by curved resilient rockers located below the bows and attached at their ends to the intermediate portions of the bows and disposed between the seats, the rockers being shorter than the bows and being more pronouncedly curved than are the bows.

In testimony that I claim the foregoing as my own, I have hereto affixed my signature.

JAS. E. TAYLOR.
